(57) **CLAIM**
The ornamental design for a radar detector with fold-out display, as shown and described.

DESCRIPTION

FIG. 1 is a perspective view of a radar detector with fold-out display in a closed position;
FIG. 2 is a front view thereof;
FIG. 3 is a back view thereof;
FIG. 4 is a right side view thereof;
FIG. 5 is a left side view thereof;
FIG. 6 is a top view thereof; and
FIG. 7 is a bottom view thereof;
FIG. 8 is a perspective view of a radar detector with fold-out display in an open position;
FIG. 9 is a front view thereof;
FIG. 10 is a back view thereof;
FIG. 11 is a left side view thereof;
FIG. 12 is a right side view thereof;
FIG. 13 is a top view thereof; and
FIG. 14 is a bottom view thereof.
The broken lines are for illustrative purposes only and form no part of the claimed design.
